UNITED STATES PATENT OFFICE.

FREDERICK EMMONS, OF SANDUSKY, OHIO, ASSIGNOR TO THE HINDE & DAUCH PAPER COMPANY, OF SANDUSKY, OHIO, A CORPORATION OF OHIO.

CARTON.

1,150,105.

Specification of Letters Patent. Patented Aug. 17, 1915.

Application filed December 7, 1911. Serial No. 664,314.

To all whom it may concern:

Be it known that I, FREDERICK EMMONS, a citizen of the United States of America, residing at Sandusky, in the county of Erie 5 and State of Ohio, have invented certain new and useful Improvements in Cartons, of which the following is a specification, reference being had therein to the accompanying drawings.

10 The invention relates to cartons and consists in the construction as hereinafter set forth.

In the drawings,—Figure 1 is a perspective view; Fig. 2 is a vertical longitudinal 15 section partly in elevation; and Fig. 3 is a plan of the blank.

My improved carton belongs to that type in which a rectangular receptacle is formed by the folding of an unslotted blank, thereby 20 producing a seamless structure.

This is particularly adapted for the shipment of bottled goods, and in case of breakage of a bottle there is no seam for the leakage of the good contents.

25 It is one of the objects of the invention to form a receptacle that may be easily handled or carried, also one which will protect the contents from heat or cold and which may be effectively closed when sealed, the 30 specific construction being as follows:

A is the blank which is preferably formed of cellular paper board and which is scored on the lines B—B, B'—B', C—C, C'—C', and D, D', D'', D''. The lines B, B', C C' 35 divide the blank into side portions E, E', end portions F, F', a bottom portion G and intermediate gore portions H, H', H'' and H'', which latter when folded on the lines D, D', D'', D''' permit of bending the ends and 40 sides to form a rectangular receptacle. The gore portions are folded adjacent to the sides E, E' and form a reinforcement for the latter, while the ends are reinforced by extensions I of the blank which are folded 45 on the lines J, J'. Thus the ends are formed of two-ply material with the fold at the upper edge, while the sides are three-ply in portions covered by the gores. The bottom 50 is reinforced by a portion K formed from a separate blank, which blank is also provided with triangular portions L forming inserts fitting adjacent to the gores H.

The construction as thus far described 55 may be shipped as a flat blank and when needed for use can be quickly set up by

folding along the score lines. To hold the folded portions in this position a fastening means is employed preferably consisting of a ribbon M of flexible fabric which passes through aligned slits N, N', N'' in the sides 60 and two plies of the gore. The inner ends of these strips are glued or otherwise affixed to an anchoring surface such as the inner face of the box and the portions outside of the box are affixed to an anchoring surface 65 such as the outer face, thereby holding the several plies together. The outer ends of the strips may also be affixed to an anchoring surface and are preferably employed for securing the cover O which is formed with 70 independent flanges P adapted to fit over the box as shown in Fig. 2.

For handling or carrying the box or carton registering apertures Q and Q' are formed in the end walls F and overlapping 75 portions I, which apertures are arranged slightly below the flanges of the cover. Thus the carton may be lifted by inserting the hands through these apertures and the two plies of the portion above the aperture 80 will possess sufficient strength to sustain the weight of the box and its contents. This portion is further strengthened by the adjacent flange P of the cover which overlaps the same.

The apertures Q if uncovered would permit a draft of air into and out from the carton which would be detrimental to the heat insulating purpose of the receptacle. I have therefore, guarded the apertures by 90 flat strips R which are arranged adjacent to the inner sides of the end walls and are affixed thereto at one point but so as not to interfere with the hand hole. Thus by affixing the strips R at their upper edges the 95 operator may insert his hand through the apertures forcing the strip inward out of the way. In normal position, the strips R lie close to the inner face of the end wall, thereby completely closing the aperture and 100 rendering the carton draft proof.

What I claim as my invention is:

1. A carton comprising a rectangular blank of the unslotted type scored and folded to form a rectangular receptacle having 105 gores between the end and side walls, and securing means for said gores comprising a ribbon passing through registering slits in the several plies, one end being affixed to the inner side and the other affixed to 110

an anchoring surface for fixedly securing said gores in folded position.

2. A carton comprising a folded blank forming a rectangular receptacle having overlapped plies, and a ribbon passing through alined slits in said plies and having one end affixed to the inner side and the other end affixed to an anchoring surface for fixedly securing said gores in folded position.

3. A carton comprising a folded blank forming a rectangular receptacle with overlapping portions formed by folded gores, a cover for said receptacle, and a ribbon passing through alined slits in the several overlapped plies, the inner end of said ribbon being affixed to the face of the inner ply and the outer end being fixed to an anchoring surface and forming a means for attaching the cover.

4. A carton comprising a folded blank forming a rectangular receptacle having overlapping plies, and a ribbon passing through alined slits in said plies and having each of its ends affixed to an anchoring surface, for fixedly securing said gores in folded position.

5. A carton comprising a rectangular

blank of the unslitted type scored and folded to form a rectangular receptacle having gores between the end and side walls, a cover for said receptacle, and a ribbon passing through alined slits in the folded gores, said ribbon having a relatively large surface at its inner end secured to the anchoring face of the inner ply of the gores, and a relatively large surface at its outer end secured to an anchoring surface to hold said gores in folded position and forming a means for attaching the cover.

6. A carton comprising a blank, scored and folded to form a substantially rectangular receptacle having gores between the ends and side walls, and a securing member passing through alined slits in said folded gores, said securing member having a relatively large flat bearing portion at each of its ends affixed to an anchoring surface for permanently securing said gores in folded position.

In testimony whereof I affix my signature in presence of two witnesses.

FREDERICK EMMONS.
